UNITED STATES PATENT OFFICE.

CLARK T. MADDOCK, OF ELYRIA, OHIO, ASSIGNOR OF ONE-HALF TO J. G. SCHULLIAN, OF CLEVELAND, OHIO.

RUBBER HEEL.

1,325,367.

Specification of Letters Patent. Patented Dec. 16, 1919.

Application filed May 15, 1919. Serial No 297,296.

To all whom it may concern:

Be it known that I, CLARK T. MADDOCK, a citizen of the United States, and a resident of Elyria, county of Lorain, and State of Ohio, have invented a new and useful Improvement, in Rubber Heels, of which the following is a specification, the principle of the invention being herein explained and the best mode in which I have contemplated applying that principle, so as to distinguish it from other inventions.

The present invention relates to rubber heels or lifts such as are used on the heels of boots or shoes, and has for one object the provision of a lift which will be retained tightly against the heel around the outside edge, and also one of increased resilience over the usual type of lift, due to the construction of center portion thereof.

To the accomplishment of the foregoing and related ends, said invention, then, consists of the means hereinafter fully described and particularly pointed out in the claims, the annexed drawing and the following description setting forth in detail certain mechanism embodying the invention, such disclosed means constituting, however, but one of various mechanical forms in which the principle of the invention may be used.

In said annexed drawing:-

Figure 1 is a top plan of my lift; Fig. 2 is a bottom plan; Fig. 3 is a section on the line 3—3, Fig. 1; and Fig. 4 is a section at right angles to Fig. 3, as shown by the line 4—4, Fig. 1.

The present lift which is designed to be attached to the heel of a boot or shoe, is shaped as shown in Fig. 1 to fit the heel on which it is to be applied, and is provided with a relatively flat upper surface 1 adapted to contact with the heel of the shoe, and to be attached thereto by means of nails passing through holes 2. Washers or small plates 3 of metal are embedded in the heel as shown in Figs. 1, 3 and 4, and are for the purpose of preventing the nails from pulling through the lift. Disposed in the upper surface of the lift is a circular recess 4. The walls 5 of the recess 4 are slanted downwardly and on a slant away from the opening thereof, whereby the recess is of larger diameter at the bottom than at the top. The bottom or base of the recess is crowned or convex, the uppermost portion or surface 15 thereof being a slight distance below the

surface of the upper face of the lift, whereby a space is left between the lift and the lower face of the heel to which it is attached.

The lower face or tread 6 of the lift is formed as best shown in Figs. 3 and 4, and is provided with a relatively flat surface 7, having a circular depression 8 in the surface thereof. This depression in cross section consists of a compound curve, being concave adjacent its circumference and convex at the center, the lowermost portion of the convex portion 9 being on the same plane as the surface of the tread.

The recess 4 and the depression 8 are concentric with each other, and, as will be seen from Figs. 3 and 4, the greatest depth of the concave portion 10 of the depression 8 in the lower face of the tread is approximately opposite the lowermost edge of the recess 4 in the upper part of the tread. It will thus be seen that the amount of material between these two points is relatively less than through any other portion of the lift, and that this part is accordingly more flexible than any other part. By constructing my lift in this manner, that is by forming the lift with a space between the surface of the heel and convex portion of the upper recess, and by making the center portion of the lift more flexible than the balance of the lift by means of the concave portion 10, the center portion of the lift is adapted to move upward if any obstruction is met while the lift is in use, thereby absorbing to a great extent any jar which would otherwise be felt.

It will also be noted that the depression 8 does not extend to the edge of the lift, but terminates a short space therefrom, thereby forming a wearing surface or flange 11 completely around the depression. By this arrangement I am able to obtain an appreciable suction between the lower face of the tread and the surface with which it is in contact, which to a very large extent eliminates the tendency to slip or slide on a wet surface, which is usually found to be the case with most lifts or heels of this class.

By constructing a rubber lift or heel in the manner shown, I have obtained a heel which is both resilient and long wearing, and by means of the space in the upper surface thereof, the convex portion in the depression on the tread surface is allowed a play or movement when the weight of a person is on it, and also equalizes the wear on the heel as the greater part of the weight will

be taken up by the outer edges. It will also be seen that a less amount of material is required than in the usual heel, at the same time retaining the resiliency and long wearing qualities so much desired in heels or lifts of this type.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. A rubber heel having a recess in the upper surface, the bottom of such recess being convex, and having a depression in its lower surface provided with a convex central portion having its central portion normally lying in the plane of the tread surface of the heel.

2. A rubber heel having a recess in the upper surface, the bottom of such recess being convex, the upper surface of such convex bottom being below the plane of the upper surface, and having a depression in its lower surface provided with a convex central portion having its central portion normally lying in the plane of the tread surface of the heel.

3. A rubber heel having a recess in the upper surface, the bottom of such recess being convex, and having a depression in its lower surface provided with a convex central portion, the lower surface of such convex central portion being in the plane of the tread surface of said heel.

4. A rubber heel having a recess in the upper surface, the bottom of such recess being convex, and having a depression in its lower surface, such depression being concentric with such recess in the upper surface of said heel, the central portion between such recess and such depression lying with-

in the planes of the upper and lower surfaces of the heel.

5. A rubber heel having substantially flat and parallel upper and lower surfaces, the upper surface thereof being provided with a recess having a convex bottom, the lower edge of such recess being of greater diameter than the upper edge, and the lower surface having a depression therein provided with a convex central portion, whereby the central portion of the heel between such recess and such depression is of greater thickness than any other portion therebetween.

6. A rubber heel having substantially flat and parallel upper and lower surfaces, the upper surface thereof being provided with a recess having a convex bottom, the lower edge of such recess being of greater diameter than the upper edge, and the lower surface having a depression therein provided with a convex central portion, whereby the central portion of the heel between such recess and such depression is of greater thickness than any other portion therebetween, the lower surface of such convex central portion being on the same plane as the lower surface of said heel.

7. A rubber heel having a recess in the upper surface, the bottom of such recess being convex, the upper surface of such convex portion being below the upper surface of said heel, and having a depression in its lower surface provided with a convex central portion, the lower surface of such convex central portion being in the plane of the bottom surface of said heel, the thickness of the material between the outermost edges of such recess and such depression being less than through any other portion of said heel whereby independent movement may be imparted to the center portion of the heel.

Signed by me this 14th day of May, 1919.

CLARK T. MADDOCK.
